FORMING MECHANISM FOR FLAT CAN BODIES

Nelson Troyer and Merton L. Dodge, Seattle, Wash., assignors to Continental Can Company, Inc., New York, N. Y., a corporation of New York

Application March 18, 1932, Serial No. 599,821

10 Claims. (Cl. 113—8)

This invention relates to can making machines, and more particularly to machines of that character known in the art as "body makers" whereby the body blanks are notched, edged and finally

5 their ends joined together in a tightly closed seam.

Explanatory to the invention it will be stated that it has become the practice of can manufacturers in certain instances, to make can bodies 10 flat in order to conserve space in packed shipments of the bodies and thus to lessen freight or transportation costs; this being especially true where large shipments are made by water such as between cities of the United States and points in

15 Alaska. Heretofore it has been the practice for such cases to initially make the can bodies in their final cylindrical form, then to flatten them for packing and shipment and subsequently, at the point of use to reform them and apply the 20 ends and covers thereto. While the present invention anticipates that can bodies, as made by the present mechanism, might have ends and covers applied thereto and be used commercially without any further shaping or reforming after

25 they leave the body maker, it is primarily intended to spread or open the flat formed bodies out to give greater capacity thereto. Therefore, the gist of this invention resides in the provision of mechanism for the manufacture of flat can bodies 30 which are adapted to be opened or spread for the application of ends and covers thereto thus to eliminate the step in the procedure as heretofore practiced of flattening the cylindrical body after formation and preparatory to shipment.

35 It is also an object of this invention to provide mechanism for the above stated purpose that is capable of high speed manufacture of can bodies, and whereby the bending of the blanks in the initial formation of the body is smoothly 40 and evenly done so that, in the subsequent final shaping, no kinks, creases or other bends will be noticeable on the body walls.

Another object is to provide a novel form of 45 clamping mechanism whereby the body blanks are shaped to one surface of the forming horn without leaving any looseness or slack in the material that might result in kinking or creasing when the wing clamps finally come into play for hooking the ends of the blanks together.

50 Another object of the invention is to provide novel features of construction in the wing clamps whereby the ends of the blanks will be bent smoothly and tightly about the opposite side edges of the horn and all slack taken out of these portions preparatory to joining their ends.

Other objects of the invention reside in the details of construction of the parts of the horn, and of the clamp devices and in their mode of operation, as will hereinafter be fully described.

In accomplishing these and other objects of the invention we have provided the improved details of construction, the preferred forms of which are shown in the accompanying drawings, wherein—

Figure 1 is a vertical section taken in the central vertical longitudinal plane of a body maker, 10 illustrating the mechanism of the present invention as associated with parts of the body maker.

Figure 2 is a plan view of the body blank feed mechanism.

Figure 3 is an enlarged cross section taken 15 substantially on the line 3—3 in Figure 1.

Figure 4 is a plan view diagrammatically illustrating the location of various parts of the present mechanism especially with reference to the geared connections of the driving mechanisms. 20

Figure 5 is an enlarged end elevation of the forming horn and wing clamps with their actuating connections.

Figure 6 is an enlarged plan, or top view of 25 the forming horn; a part being broken away for better illustration.

Figures 7, 8 and 9 are cross sectional views of the horn showing the successive operations of forming a body blank about it and clinching 30 the seam.

Referring more in detail to the drawings—

In the present illustration we have shown only those parts of the body machine that are thought necessary to give clear understanding of the invention herein claimed and which resides 35 chiefly in the construction and relationship of the forming horn and clamp devices for shaping the can bodies to the horn. In this particular type of body machine the can body forming

blanks are successively fed to the machine at one end and are intermittently advanced successively, by the action of reciprocating feed bars, to the various stations along a guideway provided 40 between parallel folder housings. The blanks move past certain devices adjacent the guideway which operate thereon during their successive

periods of rest to notch, flange and hook their edges. Finally the blanks are delivered to the shaping horn and are then wrapped and shaped 45 about it, principally by the action thereagainst of a pair of wing clamps so that their flanged, or hooked ends are overlapped, then interlocked and finally bumped to close the seam; the mechanism used being of that character disclosed in 50

55

the prior United States patent issued to Nelson Troyer under Serial No. 1,543,460 on June 23, 1925.

In the present illustration 1 designates the substantially flat forming horn about which the body blanks 2 are wrapped to shape them in body form and 3—3 designates the reciprocally actuated feed bars which advance the blanks. These bars are equipped at regular intervals with pushers 3' on their top edges which, on each forward reciprocal movement of the bars, engage with the rear edges of the blanks to push them forwardly from one station to the next one, thus to advance each blank successively to the notching and flanging stations and finally to the forming horn.

As here shown, the feed bars 3—3 are actuated through connection by a cross head 4 with a slide 4a mounted for reciprocal movement on a supporting bar 5 which extends horizontally and centrally beneath the guideway and terminates flush with the top edge of the horn; this bar serving as a central support for the body blanks as they are advanced to the horn.

A yoke like frame portion 6 of the machine, as seen in Figure 3, symmetrically overlies the forming horn and fixed centrally to this yoke is a downwardly extended bracket 7 having a hardened bar 8 set therein centrally and longitudinally overlying the axis of the horn and serving as an abutment for sustaining the horn when the bumper is driven against it for closing the seam of the body, as presently described.

The body blanks 2, when advanced to the horn are positioned beneath the bar 8; the horn at that time being spaced slightly from the bar to give sufficient clearance for reception of the body blank, then the horn is shifted upwardly and clamped tightly against the blank to hold it against any possible slippage or misalignment during the body shaping and seam closing operations.

The forming horn is rigidly supported from the upper end portion of the slide 10 that is mounted, for a definite although slight vertical movement, in a guideway 11 that is provided in a supporting bracket 12, the bracket, as seen in Figure 1, being fixed rigidly within the frame of the machine. In the lower end portion of the slide is a vertical bore 13 within which an extension piece 14 is slidably fitted. At its upper end this piece is equipped with an adjusting bolt 16 that is threaded therein with the head portion 16a of the bolt bearing against the flat base of an opening 17 that is provided in the block, and into which the upper end of the bore 13 opens. A hollow plug 18 is adjustably threaded into a hole 19 formed in the lower end of the bracket in alignment with the bore 13, and is held by a lock nut 20. A coiled spring 21 is seated in the plug and bears upwardly against the lower end of the extension piece 14 to urge the latter upwardly and to thereby shift the slide 10 and horn 1 upwardly for the purpose of clamping the body blanks between the horn and the bar 8 as they successively are advanced to forming position.

Formed in the frame of the machine, and beneath the horn is a guideway 24 in which a bumper 25 is reciprocally contained; the bumper being connected by a pitman 26 with an eccentric 27 on a rotatably driven cross shaft 28 so that, incident to the rotation of the shaft, the bumper will be driven upwardly against the horn for closing the seam of the can.

In the construction as shown in Figure 1 the slide 4a is operatively connected by means of a link 28 with the upper end of an oscillating lever 29 fixed on a supporting cross shaft 30; this shaft having a downwardly extending lever arm 31 fixed thereto and operatively connected by a rod 32 with an eccentric 33 at one end of the shaft 29. Thus the feed slides are caused to reciprocate in proper timing with action of the bumper.

After each can body blank 2 has been advanced by the reciprocal action of the feed bars past the notching and hook forming devices to a position overlying the horn, as indicated at 2a in Figure 1, it is then clamped tightly against the horn preparatory to bending the end portions of the blank downwardly about the opposite side edges of the horn and then inwardly beneath it. The horn which is substantially flat as seen best in Figure 5, is horizontally mounted. The horn also is somewhat thicker along its central portion than at the side edges which are thin and smoothly rounded. This shape makes it necessary in forming the body that instead of clamping the blank only along the center portion, as in the machine of the Troyer patent above referred to, the entire surface overlying the horn must be clamped down tightly against the horn to prevent any possible buckling when the wing clamps are subsequently brought into play to fold the blank over the edges of the horn.

As illustrated best in Figure 5, the clamp mechanism for holding the body blank tightly against the top surface of the horn comprises an inverted U-shaped yoke 35 which is vertically slidable upon a guideway 36 provided therefor in the bracket 7. The lower end portions of this yoke are formed with outwardly directed feet or flanges 35a which are adapted, when the yoke is moved downwardly, to clamp tightly against the flat surface of the blank to press it tightly against the horn as shown in Figure 5. These flanges of the yoke extend outwardly to positions substantially even with the edges of the horn. The movement of the clamping yoke 35 is effected through a certain connection with the wing clamp actuating devices 45 and will presently be more fully described.

After a body blank has been advanced to the horn and has been clamped against the top surface of the horn, the opposite end portions of the blank, which extend beyond the opposite side edges of the horn, are then bent downwardly and then inwardly so that their end hooks will be brought into overlapped relationship. This bending of the blank is accomplished by the downward closing movement of a pair of wing clamps 49—49' which are pivotally supported from the bracket 7 by pivot pins 41 and are adapted to be swingingly actuated between open and closed positions by operative connections with rotatable, driven shaft 42—42' that are mounted to extend along the opposite sides of the machine. These connections, as best shown in Figures 3 and 5, comprise two levers, 43—43' with their outer end pivotally attached as at 44—44' to the frame yoke 6, and at their inner ends are connected by link 45—45' with the wing clamps. Rods 46—46' connect the levers 43—43' at points intermediate their ends with eccentrics 47—47' on the ends of the shafts 42—42' so that as the latter rotate, the wing clamps are caused to swing between open and closed positions with respect to the horn.

As shown in Figure 4, the two shafts 42—42' are driven by suitable sets of gearing 48 from a cross shaft 49 which in turn has a geared connection as at 50 with a main drive shaft 51 extended along 75

one side of the machine. This drive shaft also has a gear connected as at 52 with the cross shaft 28, and the several connections are so arranged that the feed bars, horn, wing clamps and bumper 5 all will operate in synchronism.

The means for moving the forming horn toward and away from the clamping bar 8 is shown in Figure 1 wherein 55 designates a horizontally disposed, rotatably mounted cross shaft supporting a sleeve 56 provided at one end with a laterally extended arm 57 which, at its end rests upon the base of an opening 58 provided in the extension member 14. At the other end of the sleeve is a downwardly extended lever arm 59 provided with a roller 60 at its end arranged for rolling contact with a cam 61 that is fixed on the drive shaft 28. A spring pressed plunger 63 is mounted in a guide block 64 fixed to the machine frame to bear against lever 59 to retain the roller against the cam which is so formed that its rotating action causes oscillating movement of the levers and this in turn causes the horn mounting slide 10 first to be pulled down against the sustaining force of the spring 21, coincident with each advance movement of the feed bars, thereby to shift the horn downwardly to give the necessary clearance to permit a formed can body to be pushed from the horn and an oncoming blank to be advanced to position between the horn and clamp bar 8, then as the cam relieves the slide, the horn is moved up and clamps the blank against the bar 8 and holds it securely in place while the wing clamps 40-40' swing down to form the blank about the horn.

35 In its present form of construction the horn 1 is formed lengthwise thereof within its top side with a groove or slot 68 in which a slide bar 69 is reciprocally contained; this bar being connected at its inner end to the feed slide 4a. In its top edge the slide 69 is provided with downwardly yieldable pushers 3a whereby the formed bodies are pushed from the horn.

40 Formed centrally in the bottom surface of the horn, lengthwise thereof, is a groove 70 in which a hardened bar 71 is fitted; this bar being longitudinally grooved in its under side, as at 72, to receive the seam of the joined ends of the body blank when they are clinched by the action thereagainst of the bumper.

45 In one side edge of the horn is a longitudinal slot 75 in which an expander plate 76 is contained. This plate is permitted a slight movement inwardly and outwardly with respect to the axis of the horn. It is provided medially at inner edge, 50 with an extension 77 (see Figure 6) the ends of which slidably abut against stops 78 and 79 to hold the piece against endwise movement. A leaf spring 80 is contained within a slot 81 in the extension part and this spring bears at its 55 ends against studs 82-82 and at its center bears inwardly against the inner slot wall to thereby yieldingly urge the expander plate inwardly. The outer longitudinal edge of this expander plate extends beyond the edge of the horn body, and it 60 has a smoothly rounded outer edge as at 84 corresponding in shape to the rounded opposite side edge 84' of the horn and it is about these rounded edges that the body blanks are bent downwardly and then inwardly for joining their ends.

65 70 It will be observed, by reference to Figure 5, that each blank has oppositely bent hooks 85-86 at its ends, and when these ends are overlapped, the hooks are in position to engage each other in a holding connection incident to expanding of the 75 horn.

To expand the horn we have provided the expander bar 90 which is slidably mounted within the base of the slot 75 back of the expander plate 76. The bar 90 is connected with the feed slide 4a to cause it to move reciprocally with the feed slides 3. This bar is provided with three parallel equally offset surfaces 91-92-93 spaced longitudinally of the bar. Rollers 94 and 95 are fitted in the horn against the opposite ends of the expander plate and are held in place between the 10 stops 78 and other stops 96 spaced therefor. The arrangement of the rollers is such that, when the bar 90 is extended to its limit, as to the dotted line position 90' in Figure 6, the two rollers are in contact with the bar edge surfaces 91 and 92 15 and the expander plate 76 is permitted to move inwardly to its limit. Then with each inward reciprocal movement of the feed slides, after they have advanced a blank to the horn, and after the wing clamps have formed the blank ends about 20 the horn and the ends thereof have been overlapped, the expander bar moves inwardly to the full line position and the rollers are caused to ride upon the outwardly offset surfaces 92 and 93 of the expander bar, and thus they push the 25 expander plate outwardly. This outward movement of the plate 76 causes an increase in the effective width of the horn to expand the can body and cause the end hooks of the blank to interlock. Immediately following this engaging 30 of the hooks, the bumper is actuated upwardly against the seam to tightly close it, and to press it into the groove 72 of the plate 71 so that it will be on the inside of the can body.

35 Each of the wing clamps 40-40', as seen in Figure 5, comprises an upper frame portion 40a arranged to swing pivotally on its pivot 41. At its outer end, each frame has short inturned parts 40c within which clamp shoes 98 are pivotally mounted by pins 99.

40 These shoes have lever portions 100 extended upwardly beyond the pivots 99 and coiled springs 101 are placed between these extensions and spring mounting abutments 102 on the frames 40a to urge the lower ends of the shoes inwardly. However, the inward movement of the shoes is definitely limited by the engagement of an arm 105 extended upwardly from the shoe, as at the 45 left hand side in Figure 5, to engage with a set screw 102 adjustably mounted in a lug 106 on the 50 frame 40a. The upper frame portions of these wing clamps are of such length that when they swing downwardly to clamping position, their inturned ends will pass closely beneath the side edges of the horn. The shoes of the clamps are 55 provided at their ends with forming plates 110 with perfectly true edges 111. When the wing clamps are in raised position, they are substantially above the surface of the blank advanced over the horn. When the clamps swing downwardly, the inner edges 111 of the forming plates 110 come into contact with the blank ends closely outside of the rounded side edges of the horn and they force the blank ends downwardly and inwardly about these edges. The shoes then move 60 almost directly inwardly, as noted by the dotted line positions thereof in Figure 5, and thus the ends of the blanks are caused to be overlapped. It will be mentioned here that the movement of the clamps 40' is slightly in advance of the other 65 clamp 40 so as to place the outwardly facing hook 85 of the can blank beneath the hook 86 which is inturned.

70 After the ends of the clamping shoes 98 have bent the blank ends downwardly about the edges 75

of the horn, the forming plates then exert an inward bearing action against these bank ends, as they slide inwardly thereon, during which movement the springs 101 yield to permit this action.

5 The adjustment of the set screws 103 may be made such as to cause the clamp shoes and plates to engage the blanks very closely to the side edges of the horn and to bend the blank smoothly and evenly about these sharply rounded edges without leaving any looseness of material.

10 The action of the clamping yoke 35 is timed with respect to the action of the wing clamps by a connection best shown in Figure 5, wherein 115 designates a rod which is connected slidably at 15 its lower end to the yokes by a nut 116. At its upper end the rod 115 connects pivotally as at 117 to a lever 118. Lever 118 is pivotally fixed by a bolt 119 at one end to the frame 6, and at its other end is connected by a link 120 with the 20 lever 43 which controls movement of the wing clamps 40'. This connection provides that when the lever 43 moves upwardly it lifts the clamp 35. When it moves downwardly, it actuates the clamp downwardly, slightly in advance of the 25 wing clamp, through the medium of a coiled spring 125 that is located about the rod 115 between a collar 126 fixed thereon and the top of the yoke.

30 With the various parts so constructed and arranged, the operation of the machine, briefly described, is as follows:

35 The can body blanks 2 are advanced in proper spacing along the machine, past the notching and hook forming stations and are finally delivered directly over the horn 1, and are here clamped and held, by the slight upward movement of the horn, against the cross bar 8. Then, the clamp yoke 35 moves downwardly against the central top surface of the blank to form it to the 40 top surface of the horn. Coincident with this operation, the wing clamps 40-40' are actuated downwardly and the shoes thereof engage the end portions of the blank and these are shaped thereby to the horn. Then the expander bar 99 45 actuates the expander plate 76 outwardly to expand the body to draw the end hooks of the blank together and to hold them interlocked while the bumper comes into action to close the seam. As 50 the wing clamps then swing upwardly, the expander bar comes forwardly and permits the expander plate to move inwardly thereby releasing the body for delivery from the horn by the push finger 3' on the feed slide 69.

55 Having thus described our invention, what we claim as new therein and desire to secure by Letters Patent is—

1. In a can body forming machine, a horn having substantially flat opposite faces merging in sharply rounded opposite side edges, an abutment spaced from one face of the horn lengthwise thereof, means for positioning a body blank between the horn and abutment, means for effecting relative movement of the horn and abutment to grip the blank between them, a 60 clamp operable against the blank to shape it to the adjacent face of the horn, and a pair of wing clamps operable against opposite end portions of the blank to first bend them snugly about the horn edges and then to form them to the other face of the horn in overlapped relation for seaming.

70 2. In a can body forming machine, a horn having substantially flat opposite faces merging in sharply rounded opposite side edges, a fixed abutment bar centrally disposed lengthwise of

the horn and slightly spaced therefrom, means for positioning a body blank between the horn and bar, means for moving the horn toward the bar to grip the blank between them, a clamp shoe shaped to fit the horn at opposite sides of the bar and movable against the blank to shape it to that face of the horn, and a pair of wing clamps operable against the opposite end portions of the blank to first bend them snugly about the horn edges and then to form them to 10 the other face of the horn in overlapped relation for seaming, and a bumper operable against the overlapped portions of the blank to join them in a seam.

15 3. In a can body forming machine, a horn having substantially flat opposite faces merging in sharply rounded opposite side edges, means for positioning a body blank formed with opposite end hooks across one face of the horn, means for engaging the blank along a line medially of 20 its ends for clamping it against the horn, other means movable against the blank to shape it to that face of the horn, a pair of wing clamps movable against opposite end portions of the blank to bend them tightly about the horn edges 25 and to form them to its other face with their hooked ends overlapped, an expander plate within the horn to project from one edge thereof and movable against the blank to effect the interconnection of the hooked ends thereof and a 30 bumper operable against the ends when interconnected to close them together in a permanent seam.

35 4. In a can body forming machine, a forming horn having slightly convex upper and lower faces merging in sharply rounded opposite side edges, means for positioning a can blank across the upper surface of the horn, means engageable with the blank along a transverse line medially of its ends to clamp it against the adjacent side 40 of the horn along a medial line, a clamp movable against the blank to shape it to that surface, and a pair of swingingly mounted wing clamps movable downwardly and inwardly against opposite 45 end portions of the blank to close them about the horn; said wing clamps having yieldably mounted end shoes arranged to initially engage the blank end portions closely outside the side edges of the horn to bend them downwardly and inwardly about said edges, then to maintain an 50 inward pressure against said end portions as the clamps swing inwardly, thus to shape the said end portions to the under surface of the horn and to bring them into overlapped relation for seaming.

55 5. In a can body forming machine, a forming horn having substantially flat opposite faces merging in sharply rounded opposite side edges, means for feeding body blanks, with end hooks, to the horn, a clamp shoe operable against the blanks as delivered to the horn to form them to one face thereof, a pair of swingingly movable wing clamps, means for actuating them against the opposite end portions of a clamped blank to form them about the horn in overlapped relation said actuating means including a yielding connection to said clamp shoe for operating said clamp shoe in advance of contact of the wings with the blank ends, an expander plate slidably contained in the horn, and exposed at one edge 60 thereof, means operable to functionally move the plate to effect the interconnection of the hooked ends of the blank, and a bumper operable against the interconnected ends to join them 65 in a permanent seam.

5. In a can body forming machine, a horn mounting slide, a substantially flat horn rigidly mounted on said slide, an abutment bar fixed longitudinally of the horn, a guideway reciprocating means for feeding can body blanks successively from the guideway to the horn, means for actuating the horn mounting slide to clamp a blank, advanced by the feed mechanism, between the horn and bar, a clamp shoe operable against the blank at opposite sides of the bar to shape it to that face of the horn, a pair of wing clamps operable against the opposite end portions of the blank to shape them about the edges of the horn and to the other face thereof, with ends overlapped for seaming and a bumper operable against the overlapped portions to join them together.

10. In a can body forming machine, a forming horn having substantially flat opposite faces merging in sharply rounded edges, a bracket fixed above the horn, an abutment bar mounted in the bracket centrally above and longitudinally of the horn, a movable support for the horn, reciprocating feed mechanism for delivering can blanks to the horn, means for shifting the horn support to clamp the blanks as delivered between the horn and abutment bar, a clamp shoe slidable in the bracket and adjustable against the blank to shape it to the upper face of the horn, a pair of wing clamps swingingly mounted by the bracket and movable against the opposite end portions of the blank to bend them about the horn edges and to shape them to the under face of the horn, actuating means for the wing clamps, and actuating means for the clamp shoe operated by the wing clamp mechanism and including a yieldable member whereby the clamp shoe is actuated against the blank in advance of the wing clamps.

15. In a can body forming machine, a substantially flat horn across a face of which a can body blank may be positioned with its opposite ends extended beyond the side edges of the horn, a clamp movable against a blank so positioned to form it to that surface of the horn, a pair of swingingly mounted wing clamps, means for actuating the clamps; said clamps having pivotally mounted shoes at their ends adapted, on actuation of the clamps, to engage the extended ends of the body blank closely outside the side

edges of the horn, to bend them inwardly and tightly about the said edges, then to move inwardly therealong to cause their ends to be overlapped for seaming, and yieldable means mounted by the clamps and acting against the shoes to hold them tightly in contact with the blank ends as they move inwardly therealong.

20. In a can body forming machine, a substantially flat horn with sharply rounded opposite side edges, means for positioning a body blank across a flat surface of the horn with its opposite ends extended beyond opposite side edges of the horn, a pair of wing clamps pivotally supported from points at that side of the horn across which the blank is disposed and, respectively, closer to the side edges of the horn than to the central longitudinal line of the other surface of the horn, means for actuating said clamps against opposite end portions of the blank to close them about the horn; said clamps comprising pivotally mounted shoe at their ends extending toward each other, and yieldable means mounted by the clamps and acting against the shoes whereby they are held in positions to initially engage the blank ends closely outside the opposite edges of the horn to form the blank about the edges and whereby they are permitted to yield outwardly during the completion of the forming operation while maintaining pressure against the blank ends.

25. In a can body forming machine, a forming horn across which a body blank may be positioned for forming, and having substantially flat opposite surfaces merging into narrow opposite side edges, an abutment adapted to make line contact with said blank for clamping it against the shoe, a clamp shoe movable against the blank to form it to the adjacent flat surface of the horn, a pair of wing clamps, means operable to actuate the wing clamps against the opposite end portions of the blank to shape them about the horn in overlapped relation for seaming and means operatively connected with the actuating means for the wing clamps for actuating the clamp shoe including a yielding connection whereby said clamp shoe may be actuated to clamp the blank prior to the contact of the wing clamps with the blank ends.
